UNITED STATES PATENT OFFICE.

GEORGE WILLIAM KORN, OF CHICAGO, ILLINOIS.

DESIGN FOR A PATTERN FOR TOY SLEDS.

SPECIFICATION forming part of Design No. 25,042, dated January 7, 1896.

Application filed May 23, 1895. Serial No. 550,452. Term of patent 3½ years.

To all whom it may concern:

Be it known that I, GEORGE WILLIAM KORN, a citizen of the United States of America, residing at Chicago, in the county of Cook and State of Illinois, have invented and produced

new and original Design in Patterns for Toy Sleds, of which the following is a specification.

This invention relates to patterns for toy sleds of that class which may be formed from cardboard by suitably cutting and folding or bending the same and which are known as "kindergarten" toys, the invention itself being the design for the pattern along whose lines the cardboard is to be cut and folded.

The invention is shown in a single figure, in which—

A represents a sheet of cardboard of suitable size, on which the pattern is drawn or printed, the pattern or design itself being made up of solid and dotted lines as follows: B is a central dotted line. C C are solid straight lines parallel to and equidistant from the central line B. C' C' are straight lines parallel to the lines C C and equidistant from the central line B. D is a curved line joining the corresponding ends of the lines C C, and D'

is a solid curved line lying within and parallel to the line D and separated from it by substantially the same distance as that between each of the lines C' and the corresponding line C'.

B' B' are parallel dotted lines lying on opposite sides of the lines B and equidistant therefrom, and E E' E' E' are straight solid lines at right angles to the lines B' B' and extending from said lines respectively to the corresponding lines C' C'.

E' E' are dotted lines parallel to the solid lines E' E', and F F are solid lines extending from the inner ends of the lines E' E' to the end of the card opposite the curve D.

The essential feature of this design is the symmetrical arrangement with reference to the central line B of the lines C C D, having a form approximately like that shown. 45

What I claim as new is—

The design for a pattern for a toy sled substantially as shown and described.

GEORGE WILLIAM KORN.
